UNITED STATES PATENT OFFICE

FRANZ WÖRTMANN, OF GENEVA, SWITZERLAND, ASSIGNOR TO SOCIÉTÉ ANONYME DES ATELIERS DE SECHERON, OF GENEVA, SWITZERLAND, A CORPORATION OF SWITZERLAND

REGULATING TRANSFORMER FOR ARC WELDING BY ALTERNATING CURRENT

Application filed November 11, 1925, Serial No. 68,468, and in Germany December 23, 1924.

The invention refers to a regulating transformer for arc-welding by alternating current.

It is characterized by the fact that the arrangement of the series of connections of the transformer is such that by reducing the welding current the no-load tension is thereby positively increased automatically.

In the drawing Figure 1 is a diagrammatic plan illustrating one of the possible constructions of a transformer made in accordance with my invention.

Fig. 2 is a diagrammatic plan illustrating the relationship between the current and voltage in the secondary circuit under different conditions.

Fig. 3 is a diagrammatic plan similar to Fig. 1, but showing another form of the invention, and

Fig. 4 is also a diagrammatic plan similar to Figs. 1 and 3, but showing still another form of the invention.

Referring to Fig. 1 the magnetic frame of the transformer comprises two longitudinal limbs *a*, *b* and three transverse branches *c*, *d*, *e*. A part *f* of the primary winding *f*—*g* is fitted to the limb *a* and is connected at one end *k* with the source of electricity (not shown), at the other end, with a contact 1. Another part, *g*, of this primary winding is arranged on the limb *b* and is divided into a plurality of sections *h*, *i*, *j*. One end of section *h* is connected to a contact 1, the common ends of sections *h* and *i* to a contact 2, the common ends of sections *i* and *j* to a contact 3 and the yet free remaining end of section *j* to a contact 4. A contact arm *n* may be brought in touch with the several contacts 1 to 4 and is permanently in connection with the other pole of the source of electricity. The secondary winding *o*—*p*, feeding the arc *q*, is for one part fitted to the limb *b* and for the other part to the transverse branch *c*, in order that the dispersion may be increased. The part *f* of the primary winding therefore has a greater dispersion with reference to the secondary winding, than the part *g*.

The working of the described transformer is as follows:

If only the part *f* of the primary winding *f*—*g* which lies on the limb *a* works, then the induction of the magnetic circuit and therefore the no-load tension of the transformer are great. The leakage of the primary and secondary windings *f*—*g*, *o*—*p* on the contrary is greatest with this arrangement, so that in this case the current arising from a short circuit of the secondary winding, or the current circulating when welding is smallest. If the part *g* of the primary winding *f*—*g* lying on limb *b* is also thrown in, then the induction of the magnetic circuit is diminished, but the leakage is also diminished, so that in the case of a short circuit of the secondary winding *o*—*p* or in welding, a stronger current is produced. The proportion of the leakage of both parts *f*, *g* is under such conditions so adjusted that by reducing the welding current the no-load tension is necessarily increased positively and automatically thereby.

This is of great importance for arc welding by alternating current: In known apparatus for arc-welding by direct current or by alternating current, the regulation is such, that, when a current of low strength is used, the no-load tension is also diminished or it remains constant. This has no great importance in the case of direct current machines, for, according to the characteristic curve shown in Fig. 2, the arc tension *A* changes in a scarcely noticeable manner for short arcs and strength of current from about 60 amps. and the extent of the no-load tension needs be considered only for the lighting of the arc and the greatest possible length of arc. Very great, on the other hand, is the effect of the no-load tension on the stability of the arc in the case of welding by alternating current. In such case, the current is interrupted 100 times per second with a current having 50 alternations. In introducing every half wave, the tension must in the first place rise to a certain value (the lighting tension *B*) in order that the current might set again. The height of the lighting tension *B* is dependent to an extraordinarily great extent, on the current

strength and increases very considerably with a small current strength, as is shown by Fig. 2. For this reason known alternating current welding apparatus have a no-load tension of 70 to 90 volts, whereas for a current strength of 180 amps. for instance, 60 volts are amply sufficient. By fixing the welding current at 100 amps. the no-load tension must amount to 75 volts approximately in order to ensure a steady arc. In the case of welding with currents of less than 100 amps. the no-load tension must be still higher. The disadvantages of a high no-load tension are important, for the primary current in welding increases proportionally to the no-load tension; this demands rather large quantities of copper for the windings and the leads and also brings about a deterioration in the efficiency factor. These disadvantages are overcome in the use of the transformer herein shown and described.

In accordance with Fig. 3 the part *o* of the secondary winding is provided with contacts 11, 12, 13, 14, which may be connected by a movable contact (not shown) to leads *r*, *s*, *t*, *u* permanently connected to the ends of sections *v*, *w*, *x*, *y* of part *o*. The arc *q* is connected to those ends of parts *o*, *p* which still remain free.

If the movable contact is brought in touch with contact 11, then the no-load tension is greatest and the produced current smallest; when the movable contact lies on contact 14, the no-load tension is smallest and the welding current greatest, as, at each time a section on the limb *b* is cut off, a greater section on branch *c* is thrown in. On reducing the welding current the no-load tension is necessarily increased automatically.

In the latest constructional form (Fig. 4) both parts *o*, *p* of the secondary winding *c*—*p* are arranged on limb *b*. Part *p* is provided with contacts 21, 22, 23, 24, 25, 26 with which the movable lead *z*, leading to the arc *q*, may be connected. When connecting the arc *q* to 20 and 26 the no-load tension is smallest and the welding current greatest, when connecting it to 20 and 21 the no-load tension is greatest, the welding current smallest. An adjustment to the desired proportion between no-load tension and fixed strength of current is obtained in the manufacture of the apparatus by alteration of the air-gaps 18, 19 between the transverse branch *d* and the longitudinal limbs *a*, *b*.

In this manner the no-load tension of the regulating transformer is adjusted to the requirements of the arc, so that the greatest stability of said arc is obtained with a smallest quantity of copper.

What I claims is:

1. In an alternating current welding transformer for simultaneous regulation of voltage and current intensity, a core, pri-

mary and secondary windings on the said core, one of the said windings having a plurality of groups of turns, and means for switching in and out said groups of turns whereby a number of turns are eliminated from one winding and a greater number of turns are inserted into another winding so that there is included in the circuit with each added group a sufficiently greater number of turns to effect an increase in the no load tension and a corresponding reduction of the welding current, and vice versa.

2. In an alternating current welding transformer for simultaneous regulation of voltage and current intensity, a core, a primary winding on the said core, a secondary winding on the said core, one of the said windings being divided into a main group of turns and a plurality of auxiliary groups of turns, and means for switching in and out said auxiliary groups of turns whereby a number of turns are eliminated from one winding and a greater number of turns are inserted into another winding so that there is included in the circuit with each additional group a sufficiently greater number of turns to effect an increase in the no load tension and a corresponding reduction of the welding current, and vice versa.

3. In an alternating current welding transformer for simultaneous regulation of voltage and current intensity, a core, a primary winding thereon, a secondary winding also on the said core, the secondary winding being divided into a main group of turns and a plurality of groups of auxiliary turns, and means for switching in and out the said auxiliary groups of turns of the secondary winding whereby a number of turns are eliminated from one winding and a greater number of turns are inserted into another winding so that there is included in the circuit with each added group a sufficiently greater number of turns to effect an increase in the no load tension and a corresponding reduction of the welding current, and vice versa.

In testimony whereof I affix my signature.

FRANZ WÖRTMANN.
